AIR STREAMING FAN

Frederick W. Schmidt, Branford, Conn., assignor to The A. C. Gilbert Company, New Haven, Conn., a corporation of Maryland

Application November 13, 1950, Serial No. 195,219

15 Claims. (Cl. 230—117)

This invention relates to air streaming electric fans capable of generating and forcefully projecting a narrow straight beam of air in contrast to the usual breeze-like air flow sent out by ordinary fans to be dissipated in divergent directions.

There is much waste in the type of movement imparted to air by the conventional household fan because the air recirculates at random in eddy currents between and around tips of the air impelling blades. This inefficient action is due partially to vacuum effects set up close to the intake face of the revolving impeller blades.

One object of the present invention is to direct practically the whole volume of air displaced by the impeller blades into a narrow concentrated straight beam of air that is forcefully projected away from the fan impeller along lines parallel with the axis of impeller rotation so that the displaced air streams out to an unusually far distance from the fan at a wind velocity as high as 25 miles per hour.

A contributory object is to obtain the aforesaid results by novel principles of cooperative shape and relationship of the impeller hub and the impeller blades, in cooperation with a stationary air directing funnel shell arranged according to newly discovered principles of aerodynamic effect.

A further object is effectively to shield the whirling impeller blades of the fan so that they cannot accidentally come in contact with or damage the person of anyone near the fan even when the fan is being handled for relocating it or for aiming it in different directions while running.

A still further object is to increase the air displacing efficiency of a light three-bladed impeller of small size by novel shaping and manner of assembly of various sheet metal parts of which it is composed.

These and related objectives will appear in greater particular from the following description of a successful embodiment of the invention having reference to the accompanying drawings wherein:

Fig. 1 is a front elevation of a fan embodying the present improvements drawn on a smaller scale than its preferred actual size, a portion of the base being broken away to expose the mounting of the frame ring upon the base.

Fig. 2 is an enlarged view taken in section on either of the planes 2—2 in Fig. 1 looking in the directions of the arrows.

Fig. 3 is a side view of the fan motor, fan impeller and funnel shell assembly shown partly in section on the plane 3—3 in Fig. 1 looking in the direction of the arrows.

Fig. 4 is an enlarged fragmentary front view of the air impeller.

Fig. 5 shows a true or non-foreshortened outline view of the blade before its assembly to the impeller hub.

Fig. 6 is a view taken in section across the root end of an impeller blade looking toward the axis of the impeller from the curved line 6—6 in Fig. 4.

2

Fig. 7 is a view like Fig. 4 showing a preferred relationship of the impeller surrounding funnel shell to the path swept by the impeller blades.

Fig. 8 is a view of the impeller hub looking in the direction of arrow 8 in Fig. 7 showing the twisted and dished nature of the blade.

Figs. 9 to 13, inclusive, show truncated portions of the blade of Fig. 8 when cut off along circumferential lines designated by corresponding reference numerals in Fig. 7.

Figs. 14 to 20, inclusive, are sections delineating the profile contour of the blade on planes designated by corresponding reference numerals in Fig. 7.

The standard of this improved fan comprises a hollow base 12 incorporating a downward concavely dished top span 14 against the under surface of which is fixedly clamped by clips 16 the bottom ends of a discontinuous rigid circular frame ring 18. This ring for lightness may be hollow and formed from metal tubing. Inside the base there is mounted an electrical reactance unit (not shown) whose circuits are controlled by a conventional four position snap switch (not shown). The operating handle of the snap switch is a turnable knob 24 accessible at the front of the base for switching different strengths of current to the fan motor to produce "off," high, medium and low speeds. Current is derived through a flexible attachment cord 26.

The fan motor, impeller and funnel shell of the improved construction comprise an assembled air stream generating unit shown in Fig. 3. This may be termed the 30 air streaming unit. It is pivotally mounted and yieldably stayed on the stationary frame ring 18 at 32 for swinging adjustment about a horizontal diametral axis. It comprises a rigid assembly of an electric motor 54 carrying impeller 55, and funnel shell structure 28. This shell 35 is composite, forming a hollow annular structure consisting for lightness and manufacturing feasibility of two drawn sheet-metal parts. The circumferentially inner part or air conduit shell 46 in conjunction with the shape of impeller hub 32 forms an axially short annular Venturi 40 passageway for the air traveling through the fan in the direction of arrows F in Figs. 2 and 3 which tapers to a minimum girth of passageway at about the tip of the fan blades 90. The circumferentially outer part of the funnel shell structure is a casing shell 44. This casing shell and 45 conduit shell 46 slightly overlap at circular meeting margins in a manner to bind the funnel shell parts permanently and fixedly together.

The front opening of funnel shell 28 is spanned by a grid 48 which may be mold produced as an integral unit of stiff plastic material. The border rim of grid 48 is removably secured by screws 50 in an annular rabbet formed in the front face of casing shell 44. Screws 50 have threaded engagement with casing 44. The shape to which grid 48 is molded produces intersecting thin cross vanes 52 of sufficient depth to guide air in the single direction desired as the air passes through the grid, possessing a thinness that tapers according to principles of airfoil contour as shown in enlarged detail in Fig. 2. Grid 48 thus divides the discharge opening for the impeller driven air into cubicles of honeycomb nature. One function of these cubicles is to counteract vortex or whirling motion of the outstreaming beam of air. Tests have proven that mere parallel spaced vanes in the form of disconnected slats cannot function as an equivalent for the cubicles herein described for the purposes of the present invention. It will be noticed that the passageways for the air through the cubicles afford somewhat longer constraining conduits for the streaming air in the central region of the grid than in the border regions of the grid 55 because the vanes are deeper in the central region, the outermost edges of the vanes comprising the front face of the grid imparting to the overall grid face a shape 60 70

of somewhat spherical contour that merges pleasingly with and forms a continuation of the bordering front face contours of the casing 44.

The torpedo shaped body of the fan motor is designated 54. It derives its support coaxial with conduit 46 solely from the funnel shell structure 23 through the medium of four stiff spider fins 56 each of triangular shape and which place a substantial portion of the length of the motor body in outboard or rearwardly offset relation to funnel shell 23. Fins 56 are equally spaced about the motor body and are fixed to the case 60 of the latter by lugs 58 welded thereto, and with the strengthening assistance of three hoops 70, 72, 74 of round wire, increasing in diameter in the order named. These hoops are nested in notches in the edges of the spider fins. Fins 56 are fixed to conduit shell 46 by holding screw 66 engaging nuts 68 and surrounded by vibration deadening washers 64 of distortable resilient material.

Fig. 3 shows the impeller to include a central hollow stud shaft 76 removably fixed on the motor shaft 78 by set screw 80. Fixedly supported at the front end of stud shaft 76 is the nose end of the bullet-shaped hollow hub 82 of the impeller whose sheet metal wall is lanced in three circumferentially spaced locations to form the ventilating openings 84. The tongues 86 which are struck inward at these openings revolve in unison with the impeller and act as fan blades to set up a region of partial vacuum inside the hub 82 which sucks ambient air into the motor case 60 through apertures 85 in the rear end thereof, thence past the body of the motor inside of the case for cooling the motor, which air is finally scooped outward from the hub 82 through openings 84 by tongues 86 and joins the main stream of air generated by the impeller blades 90. A hole 88 in the hub wall gives access for a screw driver to the set screw 80.

The mutually facing convexities of conduit 46 and impeller hub 82 in all diametral planes containing the axis of rotation of the impeller produce an annular passageway therebetween of Venturi nature whose narrowest portion is spanned by each of three impeller blades 90. But it will be noticed that such narrowest portion of the annular passageway is not concentrated at the axial end of the passageway having the smallest overall girth but is distributed well over the total axial length of the passageway which calls for the blades 90 to extend forward or toward the left in Fig. 3 as they proceed outwardly from the hub and sweep such full axial length.

The impeller blades 90 are alike, having a root portion 92 of maximum transverse blade width relatively near the impeller axis and having in general the outline shape of a partial crescent delineated by a convex air entering or leading edge 98 and a concave trailing edge 100, both of which edges extend from the root portion 92 of the blade and converge throughout the arcuate length of the blade and form a trailing end portion 101 of the blade terminating in a blunt trailing tip 102 relatively distant from the impeller axis. The trailing edge 100 is the only part of the blade which lies in a plane represented graphically by the broken line P common to Figs. 14 to 20, inclusive. The trailing end portion 101 of the blade aligns in general with its own orbit of circular travel and its tip 102 points backward with respect to the direction R of blade travel. Between the leading edge 98 of the blade and the trailing edge 100 of the blade the front or air-attacking surface 104 of the blade extends with concave curvature from one to the other of said edges in all planes that are normal to the blade edges or crosswise the blade as shown in Figs. 14 to 20, inclusive, as well as in all paths that are shown in Figs. 9 to 12, inclusive.

In addition to delineating the contour of the blade surfaces, Figs 8 to 12, inclusive, serve to show the twisted nature of the blade wherein its angle A of relatively steep pitch in the root portion 92 of the blade merges into an

angle B of relatively mild pitch in the trailing portion 101 of the blade.

The back or trailing surface 106 of the blade is convex and of contour corresponding to that of the front or air attacking concave front surface 104 of the blade if the blade be formed from thin sheet metal of uniform thickness. This results in its being fashioned on airfoil or streamlined principles of contour. A very thin blade so formed from sheet metal will on the "cat's ear" principle possess the advantageous stiffness of a tapering trough explained in U. S. Patent Reissue No. 21,443, granted May 7, 1940 to Alfred C. Gilbert et al. Such trough in the present improved shape of blade extends continuously along the arcuate extent of the blade from its root end portion to its trailing end portion. The greatest depth of the trough lies approximately along the curved median line M—M of the blade in Fig. 5. Figs. 14 to 20, inclusive, show this trough to be deepest in the root portion of the blade and to become progressively less deep at the trailing tip 102. If it is desired to make the blade of molded or cast solid material, the trailing surface 106 need not be changed but the front or air attacking surface 104 can be such as would be generated by a straight line radial to the axis of propeller rotation swinging about said axis while simultaneously advancing along said axis. An air attacking blade surface so generated will be that of a helical ramp.

The root end of each blade has at least three fastening tongues such as 94 which project edgewise from the blade 30 and penetrate closely fitting slots 96 in the impeller hub to be bent over in opposite directions close to the inner surface of the hub wall as shown in broken lines in Fig. 6, where if preferred they may be copper brazed in place.

35 The aerodynamic action of blades having the improved shape and disposition with respect to their path of travel provided by this invention as shown in Figs. 8 to 20, inclusive, is as follows: The air as it enters funnel shell 46 through the swirl baffling fin planes 56 is immediately cleaved near the right end of the annular Venturi passageway by the convex leading edge 98 of each impeller blade traveling in the direction of arrow R in Figs. 4, and 7 to 14, inclusive. The root portion of this leading edge at and near the hub 82 first attacks the air after which the remaining portion of the edge slices into the air at a slant or with a diminishing angle of attack along the trailing end portion of the blade thereby to compensate for the higher linear speed of those portions of the blade located at a greater radial distance from the impeller axis. It will be apparent from the arrows R appearing in all of Figs. 9 to 13, inclusive, that with respect to the direction of travel of the blade no portion of the concave front surface 104 of the blade forms a hollow or pocket following the entrance of the leading edge of the blade 55 into the air. Such is undesirable because it could set up the disturbing suction or back-dragging effect of a partial vacuum pocket existing in front of the blade. The blade advances into the air with relatively less linear speed at its root end portion which has the greater air displacing 60 area and with relatively greater linear speed at its trailing end portion which has less air displacing area so that air is displaced with uniform volumetric effect at all radial distances from the axis of rotation as it is scooped up by the curved trough of the blade and the duty of displacing the air is uniformly distributed all over the working blade surface. Backward escape of the air around the trailing edge of the blade is minimized and maximum pick up and displacement of air occurs with a relatively small impeller. As the blade advances ahead 65 of space from which it has displaced air it leaves a minimum of vacuum in its path. This is because the trailing end portion 101 of the blade tapers all the way to its trailing tip 102 and also because the trailing end portion aligns longitudinally with its own circular path of travel 70 while pointing backward with respect to its direction of

travel wherefore the blade withdraws gradually rather than abruptly out of the space from which it has displaced air.

When the stream of air efficiently generated by this improved impeller becomes discharged at a resulting high velocity through the cubicles defined by grid vanes 52, practically all swirling motion of the stream that then exists is baffled by the considerable depth and crosswise intersecting relationship of the vanes 52. The spherical contour of the front face of the grid appearing at the extreme left in Fig. 3 produces a longer extent of the grid vanes 52 in the path of air flow near the center of the grid than at the circumferential margin of the grid and this contributes to the effectiveness of the grid in breaking up and rectifying the swirling of the air stream so that its distance of projected travel away from the fan will be increased. The combined result of the foregoing described features upon the generated stream of air is to project it in a narrow, non-flaring, stream flowing forcefully in a concentrated beam in whatever single direction the fan is aimed.

The particular construction by which the fan shell 28 is pivotally supported at 32 upon the frame ring 32 is the subject of claims in a copending application, Serial No. 188,524, filed October 5, 1950, now Patent No. 2,660,368 granted November 24, 1953. The particular construction of the fin plates 56 and their combination with the funnel shell 46 and motor 54 is the subject of claims in a copending application, Serial No. 188,523, filed October 5, 1950, now Patent No. 2,672,280, granted March 16, 1954.

The following claims are directed to and intended to cover not only the precise shapes and relationship of parts which are herein disclosed to explain the underlying principles of the invention but all fair equivalents thereof falling within a broad interpretation of the language of the claims.

I claim:

1. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, the blade-spanned shortest distance between said impeller hub and said conduit shell lying across said passageway in a direction that is obliquely disposed in relation to said axis of rotation, whereby the whole body of each of said impelling blades sweeps through an axial extent of said passageway greater than the axial extent of any individual blade at any given distance from said axis thereby to work against air drawn through said passageway substantially throughout the axial extent of said passageway.

2. An air streaming fan embodying in combination, a rotary impeller hub tapering throughout a major portion of its axial length from a relatively large end to a relatively small end and outwardly presenting between said hub ends a convex profile in planes containing its axis of rotation, a funnel-shaped stationary air conduit shell coaxial with and encompassing said hub tapering throughout a major portion of its axial length from a relatively large end to a relatively small end and inwardly presenting between said shell ends a convex profile in said planes facing said outwardly convex profile of said hub, said lengths of hub and shell being concordant in axial position and forming therebetween an annular air passageway increasing in radial width in both axial directions from an intermediate point in the length of said passageway having a minimum width substantially no greater than the maximum transverse dimension of said

hub, and air impelling blades having their root ends mounted on said hub extending therefrom in a direction to span and sweep around in said minimum width of said passageway.

3. An air streaming fan as defined in claim 2, in which each of the said impeller blades is of dished contour making one face of the blade concave and the other face thereof convex, the blade being so shaped and so pitched with respect to the plane of impeller rotation that said concave face of the blade attacks the air without being reentrant with respect to the air attacked thereby.

4. An air streaming fan as defined in claim 2, in which the nearest together points of the said shell and hub convexities occur respectively at the said relatively small end of said shell and at a point on said hub substantially midway the axial length of the latter, wherefore the said annular passageway is relatively wider in a radial direction at both of its ends than intermediate its axial length.

5. An air streaming fan embodying in combination, a rotary impeller hub outwardly presenting a convex profile in planes containing its axis of rotation, a funnel-shaped stationary air conduit shell encompassing said impeller hub inwardly presenting a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades having an arcuate curvature extending backward with respect to the direction of rotation of said hub defined throughout by a convex leading edge of the blade and a concave trailing edge of the blade, said blades being of such twisted shape that the portion of each blade nearest said hub has relatively steep pitch and the portion of each blade nearest said conduit shell has relatively less pitch in relation to the plane of rotation of the impeller hub.

6. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades being longitudinally of arcuate curvature and tapering like a partial crescent from a crosswise broadest root end portion of the blade at said hub to a crosswise narrowest trailing end portion of the blade at said conduit shell.

7. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades having an arcuate curvature extending backward with respect to the direction of rotation of said hub defined throughout by a convex leading edge of the blade and a concave trailing edge of the blade.

8. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said planes and of sufficiently large compass to leave an annular air passageway of progressively varying size along said planes between said shell and said hub, and air im-

peiling blades carried by said hub in positions to span and circularly sweep substantially the narrowest portion of said annular passageway, each of said blades having the general outline shape of a partial crescent delineated by a convex air entering edge and a concave trailing edge both of which edges extend from an air attacking root portion of the blade having maximum breadth relatively near said axis of rotation and converging toward and throughout an elongate trailing end portion of the blade relatively distant from said axis, said trailing end portion of the blade aligning with its orbit of travel about said axis and pointing backward with respect to its direction of travel, the air attacking surface of said blade between said blade edges extending with concave curvature from one to the other of said edges of the blade in all planes normal to said edges.

9. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades having an outline shape that is arcuately curved throughout the length of the blade and whose length tapers like a partial crescent merging from a relatively broad root end portion of the blade into a bluntly pointed relatively narrow tip portion of the blade, one surface of said blade being contoured to form a smooth trough progressively extending throughout said arcuate length of the blade and diminishing in depth from said root end portion to said tip portion of the blade.

10. An air streaming fan embodying in combination, a rotary impeller hub outwardly presenting a convex profile in planes containing its axis of rotation, a funnel-shaped stationary air conduit shell encompassing said impeller hub inwardly presenting a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades having an arcuate curvature extending backward with respect to the direction of rotation of said hub defined throughout by a convex leading edge of the blade and a concave trailing edge of the blade, said leading edge of the blade progressing from a relatively more radial disposition near the said impeller hub to a relatively more circumferential disposition in the said trailing end portion of the blade.

11. An air streaming fan embodying in combination, a rotary impeller hub outwardly presenting a convex profile in planes containing its axis of rotation, a funnel-shaped stationary air conduit shell encompassing said impeller hub inwardly presenting a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, each of said blades having an arcuate curvature extending backward with respect to the direction of rotation of said hub defined throughout by a convex leading edge of the blade and a concave trailing edge of the blade, said concave trailing edge of the blade lying substantially completely in a single plane.

12. An air streaming fan embodying in combination, a rotary impeller hub outwardly presenting a convex profile in planes containing its axis of rotation, a funnel-shaped stationary air conduit shell encompassing said impeller hub presenting inwardly a convex profile in said

planes and of sufficiently large compass to leave an annular air passageway of progressively varying size along said planes between said shell and said hub, and air impelling blades carried by said hub in positions to span and circularly sweep substantially the narrowest portion of said annular passageway, together with a grid extending across said conduit shell at the air discharge side of said air impelling blades comprising intersecting cross vanes of substantial depth dividing the pathway for the discharged air into cubicle passageways thereby to inhibit swirling in the stream of air projected away from the fan.

13. An air streaming fan embodying in combination, a rotary impeller hub outwardly presenting a convex profile in planes containing its axis of rotation, a funnel-shaped stationary air conduit shell encompassing said impeller hub inwardly presenting a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, together with a grid extending across said conduit shell at the air discharge side of said air impelling blades comprising intersecting cross vanes of substantial depth dividing the pathway for the discharged air into cubicle passageways thereby to inhibit swirling in the stream of air projected away from the fan, said vanes being of air foil shape tapering in thickness in the direction of air flow therethrough.

14. An air streaming fan embodying in combination, a rotary impeller hub outwardly presenting a convex profile in planes containing its axis of rotation, a funnel-shaped stationary air conduit shell encompassing said impeller hub inwardly presenting a convex profile in said planes and of sufficiently large compass to leave an annular air passageway of progressively varying size along said planes between said shell and said hub, and air impelling blades carried by said hub in positions to span and circularly sweep substantially the narrowest portion of said annular passageway, together with a grid extending across said conduit shell at the air discharge side of said air impelling blades comprising intersecting cross vanes of substantial depth dividing the pathway for the discharged air into cubicle passageways thereby to inhibit swirling in the stream of air projected away from the fan, the front face of said grid most remote from said impeller hub being comprised of the edges of said vanes and convexly contoured in a manner to produce a greater length of said cubicle passageway near the center of the grid than near the margin of the grid.

15. An air streaming fan embodying in combination, a rotary impeller hub outwardly presenting a convex profile in planes containing its axis of rotation, a funnel-shaped stationary air conduit shell having relatively small and large ends and encompassing said impeller hub presenting inwardly a convex profile in said planes facing said convex profile of said hub and of sufficiently large compass to leave an annular air passageway of progressively varying size along said planes between said shell and said hub, and air impelling blades having their root ends mounted on said hub so that said blades are positioned to span and sweep around in the portion of said annular passageway that intervenes between the nearest together points of the mutually facing convexities of said hub and of said shell, together with an electric motor carrying the said impeller hub, said motor having a hollow casing containing ventilating openings in its end opposite said impeller hub, and said impeller hub being perforate and hollow and carrying air impelling tongues on the interior thereof arranged to induce a motor ventilating flow of air inward of said casing through said openings and outward through said perforate impeller hub.
